STOKER

John R. Graves, Bergenfield, N. J., assignor, by
mesne assignments, to The Standard Stoker
Company, Inc., New York, N. Y., a corporation
of Delaware

Application August 5, 1936, Serial No. 94,357

13 Claims. (Cl. 110—104)

This invention relates to stokers of the type employing a conveyor screw for delivering coal to a distributing device positioned at an opening in a furnace wall.

5 It is the principal object of this invention to prolong the life of vital stoker parts upon which coal lies in certain dormant zones during passage of the bulk of the coal to the distributing device, and in which dormant zones the corrosive action 10 of the coal causes such vital stoker parts to deteriorate rapidly.

More specifically, the invention contemplates the provision of guard plates which are in a novel 15 relation with the stoker conduit and vital parts of the distributing device whereby the objectionable dormant zones of coal and the attendant difficulties are eliminated.

As a further object thereof, the invention consists in the provision of guard plates which constitute forward extensions of a cylindrical conduit 20 at the juncture thereof with a conduit discharge mouth which is of somewhat angular configuration in transverse cross section.

Other objects are to provide the novel guard 25 plates, their mode of attachment to the distributor head and their novel relation with vital stoker parts.

In the drawing:

Fig. 1 is a vertical longitudinal section through 30 the delivery end of a stoker and the adjacent portion of a furnace showing the invention as applied thereto;

Figs. 2, 3 and 4 are views in section taken along the lines 2—2, 3—3, and 4—4, respectively, of 35 Fig. 1; and

Fig. 5 is a fragmentary view similar to Fig. 4, illustrating a modification.

Referring to the drawing, there is shown at 40 10 a portion of an upstanding wall of a boiler firebox 8 having a firing opening 11 therein to which fuel is advanced by the conveyor screw 12. The screw 12 is housed within the inclined stoker conduit 13 which opens endwise into the firing opening 11. At its forward end the stoker 45 conduit 13 is provided with a mouth portion 14 extending across the lower portion of the firing opening. Any preferred construction may be employed to attach the conduit 13 to the wall 10 for the purpose of maintaining the conduit mouth 50 portion 14 in communication with the firing opening 11. In transverse cross section, rearward of its mouth portion, the interior of the conduit 13 is circular in cross section. Immediately forward of its circular portion, the conduit changes 55 abruptly to an inverted U-section, and in its for-

ward extent changes gradually to the rectangular cross section, as illustrated in Figures 4, 3 and 2.

Forward of its circular portion, the bottom of the stoker conduit 13 is open between the side walls 15, 16. A distributor member or head 17 having a flat upper surface is detachably disposed, as will presently appear, in the opening 9 at the upper forward end of the stoker conduit 13 to form a floor portion for the delivery end of the conduit. It will be observed that the distributor head 17 extends beyond the conduit mouth portion into the firing opening 11 to a point intermediate the inner and outer surfaces of the firebox wall 10. At its forward end the distributor head 17 detachably supports the table 18.

A plurality of vertically spaced horizontal rows of jet openings 19 extend across the upright face 20 of the distributor head 17. These jet openings 20 communicate with one or more chambers 21 formed within the distributor head 17 beneath the upper surface thereof. Steam or any other suitable pressure fluid is supplied to the chambers 21 through intake openings such as 22. Fuel advanced by the conveyor screw 12 is moved over the upper surface of the distributor member 17 into the zone of action of the pressure fluid blasts discharging from the jet openings 19, which blasts serve to project the fuel across the table 18 for 30 distribution over the firebed in the firebox. Adjustable deflector vanes 23, 24 constitute forward continuations of the conduit side walls 15, 16, respectively, and they are mounted upon pivot pins such as 25 whereby each may be set at any desired angle with respect to the upright face 20 of the distributor head 17 for the purpose of 35 controlling the delivery of fuel to the distributing device.

The distributor head 17 is seated upon ledges 40 26 which extend inwardly from the side walls 15, 16 and ledges 26a extending forward of the transversely disposed boss 27 depending from the lower forward edge of the tubular portion of the stoker conduit, said side walls and boss 27 defining the 45 opening 9 in the bottom of the stoker conduit 13. Adjacent the boss 27, each side wall 15, 16 has threaded thereinto a screw 28, the tapered inner portion 29 of which is arranged to press firmly against the upper surface of the distributor head 17 and also against a lug such as 30 whereby 50 upward and fore and aft movement of the distributor head 17 is restrained during normal operation of the stoker. Whenever it is desired to remove the distributor head 17 from its position 55

over the opening 9, the screws 28 are threaded outwardly a distance to clear the lugs 30, whereupon the mechanic may remove the head by drawing the same forwardly and upwardly into the firebox a slight distance. It will be understood that the firedoor 31 is thrown open during this operation.

Due to the fact that the change in cross sectional configuration of the stoker conduit from its circular portion to its inverted U-shaped portion is abrupt, a certain amount of coal, heretofore, in passing from the circular section into the inverted U-shaped section, would remain dormant along the side walls 15, 16 of the stoker conduit 13 and also along the lateral sides of the upper surface 32 of the distributor head 17. This dormant zone of coal extends a substantial distance forward of the circular section of the conduit 13.

It has been experienced in actual service of the described stoker device, prior to this invention, that the coal lying more or less dormant along the lateral sides of the distributor head 17 will cause corrosion of its surface 32. Furthermore, since the coal along the corroded portions of the surface 32 is not subject to the direct impelling action of the conveyor screw 12, whatever forward movement of the coal in these zones occurs is accompanied by a sliding action of the coal lumps along the corroded portions of the surface. The coal sliding, or being pushed, slowly along the affected portions of the surface 32 is under greater pressure at these zones than at other portions of the stoker conduit 13; consequently, greater friction results so that within a comparatively short time the surface 32 wears through to an extent that the cored chambers 21 become exposed and the distributor head 17 becomes unfit for further service.

In order to prolong the life of the distributor head 17, I provide a simple and efficient means for guarding the lateral sides of the surface 32 from the corrosive action of the coal. This means includes a guard plate 33 mounted upon the upper surface of the distributor head 17 and extending forwardly from the rearmost edge of the surface 32 and at each lateral side thereof. The surface 32 of the distributor head 17, as shown in Fig. 1, comprises two surface portions, an inclined rearward surface portion 40 and a forward surface portion 41 at a lesser angle of inclination with respect to the horizontal than surface portion 40. On the outer portions of the forward surface portion 41 are formed ridges 42 and 43 constituting prolongations of the rearward surface portion 40, the ridges 42 and 43 having plane upper surfaces in the plane of the rearward surface portion 40. Each guard plate 33 has a plane under surface providing surface contact between the aforesaid under surface of the guard-plates 33 on the one hand and the rearward surface portion 40 and the surfaces of the ridges 42 and 43 of the distributor head 17 on the other hand. Each guard plate 33 has an arcuate-shaped wall 34, the radius of curvature of which approximates that of the circular portion of the stoker conduit. At its rearmost portion, the upper edge 35 of each arcuate wall 34 extends to a maximum above the upper surface of the surface 32, and is inclined toward its lower edge. The upper edge 35 of each arcuate wall 34 throughout the length thereof contacts the respective side walls 15, 16 of the stoker conduit.

The guard plate may be constructed, if desired, with the arcuate walls 34 thereof joined at their

inner portions, or, as shown in Fig. 5, these arcuate walls 34a may be made integral with the upper surface 32a of the distributor head 17a. However, it is preferred that the arcuate walls 34 at the sides of the stoker conduit 13 be made separable from each other in order to facilitate their application to the distributor head 17.

As illustrated in Figures 3 and 4, each guard plate 33 is provided at its under side with an enlarged portion such as 36 into each of which a screw 37 is threaded. Each screw 37 passes through the upper surface 32 of the distributor head 17 and detachably secures each guard plate to the distributor head 17. Before securing the guard plates 33 to the distributor head 17, the former are each fitted into the stoker conduit 13 and their positions carefully scribed upon the upper surface 32. Whereupon, the distributor head 17 is removed from the stoker conduit in the heretofore described manner, the guard plates 33 placed upon their scribed outlines and holes drilled in the distributor head 17 and tapped in the guard plates 33 whereby the screws 37 are passed through the head 17 and threaded into the guard plates for securing the latter to the former.

From the foregoing, it will be apparent that the herein described construction prolongs the life of the distributor head 17 by insuring that coal is moved constantly therealong because the zones where coal may lie dormant have been effectively eliminated.

I claim the following as new and useful:

1. A pressure fluid distributor head for a stoker comprising a flat upper surface, means providing a plurality of pressure fluid chambers underneath said upper surface, a wall depending from one end of said upper surface and having a plurality of pressure fluid discharge orifices therein communicating with said chambers, and an arcuate wall at each side of said upper surface extending upwardly therefrom, said arcuate walls extending forwardly from the end of said upper surface remote from the said depending wall and being spaced inwardly from the side edges of said upper surface at the last named end thereof and diverging to the side edges of said upper surface at they extend forwardly.

2. A pressure fluid distributor head for a stoker comprising a flat upper surface, means providing a plurality of pressure fluid chambers underneath said upper surface, a wall depending from one end of said upper surface and having a plurality of pressure fluid discharge orifices therein communicating with said chambers, and an arcuate wall at each side of said upper surface formed integrally therewith and extending upwardly therefrom, said arcuate walls extending forwardly from the end of said upper surface remote from said depending wall and being spaced inwardly from the side edges of said top surface at the last named end thereof and diverging to the side edges of said upper surface as they extend forwardly.

3. A guard plate for a stoker distributor head comprising an arcuate wall having the same radius of curvature throughout its length, the bottom of said arcuate wall throughout the length thereof having a plane surface, said arcuate wall at one end of said guard plate being at a maximum distance above the aforesaid plane of said bottom surface and thence sloping toward said bottom surface, said bottom surface being provided with threaded openings.

4. In combination with a stoker conduit hav-

- ledges extending laterally inward of the lower ends of said upright side walls and forward of the lower forward end of said tubular portion, a distributor head seated on said ledges between the lower ends of said side walls and immediately forward of the lower forward end of said tubular portion, said distributor head including a flat upper surface constituting a support for coal passing through said conduit, and a separable upstanding wall located within and at each side of said delivery portion immediately forward of the tubular portion of the stoker conduit, said upstanding walls being detachably secured on the upper surface of said distributor head spaced inwardly at their lower edges from the side walls of said delivery portion and curving upwardly and outwardly to said side walls.
- 10 12. In combination with a stoker conduit having a tubular portion provided with a bottom wall, the inner surface thereof being arcuate in transverse cross section, and a delivery portion immediately forward of said tubular portion, said delivery portion including upright side walls, ledges extending laterally inward of the lower ends of said upright side walls and forward of the lower forward end of said tubular portion, a distributor head seated on said ledges between the lower ends of said side walls and immediately forward of the lower forward end of said tubular portion, said distributor head including a flat upper surface constituting a support for coal passing through said conduit, and a separable
- 15 20 25 30

arcuate upstanding wall located within and at each side of said delivery portion immediately forward of the tubular portion of the stoker conduit, said arcuate walls being detachably secured on the upper surface of said distributor head spaced inwardly at their lower edges from the side walls of said delivery portion and curving upwardly and outwardly to said side walls.

13. In combination with a stoker conduit having a tubular portion provided with a bottom wall, the inner surface thereof being arcuate in transverse cross section, and a delivery portion immediately forward of said tubular portion, said delivery portion including upright side walls, ledges extending laterally inward of the lower ends of said upright side walls and forward of the lower forward end of said tubular portion, a distributor head seated on said ledges between the lower ends of said side walls and immediately forward of the lower forward end of said tubular portion, said distributor head including a flat upper surface constituting a support for coal passing through said conduit, and an arcuate wall located within and at each side of said delivery portion immediately forward of the tubular portion of the stoker conduit, said arcuate walls being integrally formed with the upper surface of said distributor head spaced inwardly at their lower edges from the side walls of said delivery portion and curving upwardly and outwardly to said side walls.

JOHN R. GRAVES.
